AIR TEMPERING UNIT

John V. Falco, Everett, Mass.

Application September 25, 1936, Serial No. 102,597

2 Claims. (Cl. 257—137)

This invention relates to unit type heating and cooling apparatuses and, more particularly, to power driven units for diffusing heated or cooled air.

5 One of the primary objects of the present invention is to construct an improved ventilating unit in which the air passing therethrough is discharged throughout a radius of 360 degrees and thus secures even distribution of large volumes of treated air.

10 Another object of the invention is the provision of sufficient contact of the air moving through the unit with the temperature regulating means to insure sufficient heating or cooling to accomplish adequate changes in temperature in the room in which the unit is placed.

15 A still further object of the invention is to construct the unit with a minimum number of parts that are readily fabricated, rugged in construction and economical to operate.

20 In the drawings:

Figure 1 is a front elevation partly broken away of a unit adapted to be suspended from the ceiling.

25 Figure 2 is a vertical section taken on line 2—2 of Figure 1.

Figure 3 is a front elevation also partly broken away of a modified form of the unit.

30 Figure 4 is a vertical section taken on line 4—4 of Figure 3.

Figure 5 is a vertical cross section of a further modified form of unit which is adapted to be supported on the floor.

35 Referring to the form of unit illustrated in Figures 1 and 2, it will be seen that it consists of a pair of spaced apart circular front and rear plates 1 and 2 respectively which form a casing enclosing the blower and temperature transfer elements.

40 The circular casing plates 1 and 2 are secured in fixed spaced relation through the medium of a plurality of tie rods 3 positioned around the circumference of the casing. The rear casing sheet 2 is apertured to provide a passageway for shaft 4 of motor 5, the latter being supported on bracket 6 also affixed to the back casing sheet.

45 The front sheet of the casing has an opening 7 formed therein whose axis is concentric with relation to shaft 4. An inwardly curved annular intake throat 8 is secured in the front opening and terminates adjacent the outwardly flared flange 9 formed on the inner edge of disc 10 affixed to the outer ends of radially extending fan blades 11. The blades 11 are preferably 55 oblique in contour and are integrally formed on

circular back plate 12 which is provided with an integral hub 13 and affixed to motor shaft 4. This type of fan construction draws in air axially through opening 7 and discharges the tempered air at a considerable velocity throughout its entire periphery so as to insure a uniform distribution and diffusion of rapidly moving fluid throughout 360 degrees.

5 The front and back casing sheets 1 and 2 are outwardly flared near their circumferences and in the enlarged channels thus formed are secured continuous circular headers 14 and 15. Also disposed in these enlarged edge sections are a series of transverse tubes 16 in open communication with the headers 14 and 15. When a suitable 10 heating or cooling medium is introduced into the header 14 through upper inlet connection 17, it circulates through the headers and connecting tubes 16 outwardly through connection 18. This arrangement insures a proper distribution of the 20 heating or cooling medium through all portions of the headers and transfer tubes.

The series of spaced circular temperature transfer fins 19, supported on the series of transfer tubes 16, are constructed of discs fabricated 25 from copper, aluminum or other thermal conducting metal. Each disc is perforated with a series of flared openings 20 through which the tubes 16 are inserted and soldered thereto.

Thus air drawn in from the room is pumped 30 outwardly through the series of parallel passages defined by the spaced discs 19 and consequently an excellent thermal transfer is accomplished between the heated or cooled discs 19 and the air contacting the discs. Steam, hot water, hot 35 air, chemical transfer liquids, refrigerants, cold water or cooled air may be introduced into the inlet connection 17 and discharged through the opening 18. As before stated, any of these heating or cooling mediums is uniformly circulated 40 throughout the headers and connecting tubes to transfer heat or cold to the discs 19 so that all air passing through the unit is properly tempered.

The unit thus described is of a type particularly designed to be supported from the ceiling of a room by means of arms 21 which are fastened to the front and rear of the casing by the tie rods 3.

45 The modified form of unit illustrated in Figures 3 and 4 is of essentially the same construction as the unit previously described. However, in this form, the blower 25 driven by motor 26 is mounted in a square casing and includes front and rear circular headers 29 and 30 joined by 50

55

transfer tubes 31 carrying spaced circular fins 32 similar to the unit just described.

This modified type of unit is used where it is desirable to have a portion or all of the tempered air directed into ducts or conduits leading to sections of the room which would not be affected by a unit discharging throughout 360 degrees. In the modified unit, separator or baffle plates 33 are secured between the front and rear casing sheets 27 and 28, the plates extending inwardly from each corner thereof to equi-spaced points on the periphery of the blower 25. The plates 33 bisect the space between the front and back sheets and are slightly wider at their outer ends where the casing is enlarged, the baffles being cut away at 34 to accommodate the transfer tubes 31 and discs 32.

It will be evident from this description that in operation an equal volume of tempered air is discharged through each of the passages formed by spaced pairs of baffle plates. With this construction, the unit may be used to merely diffuse air through all four passages, or the passages may be connected to ducts while others are left open 25 to diffuse air in the immediate vicinity of the unit.

The second modification of the unit shown in Figure 5 also makes use of a spaced annular header and circular disc construction shown in the other two forms. This type of unit, however, is adapted to be positioned on the floor of a room and, consequently, the air is horizontally diffused through the conditioning portion indicated by the numeral 35 by being mounted in the upper portion of a tubular casing 36 secured on floor brackets 37. A propeller type blower 38 comprising a motor and propeller blades is affixed to a bracket 39 fastened to the bottom plate 40 of the casing 36. The curved inlet 41 directs the

air forced by the blower 38 upwardly through the casing where it comes in contact with the horizontally positioned conditioning discs as indicated by the arrows.

The conditioning unit 35 is secured in the upper end of the casing 36 by means of the flanged section 42 and air is prevented from rising through the center of the discs by outwardly flared top plate 43. This form of unit discharges large volumes of tempered air throughout 360 degrees in a plane parallel to the room flow.

What I claim is:—

1. An air tempering unit including a pair of spaced parallel circular headers through which a heating or cooling medium is adapted to circulate, a series of transverse conduits connecting said headers around their circumferences, square cover sheets attached to the outer sides of said headers, an air impeller mounted interiorly and centrally of said cover sheets, the front cover sheet being apertured to provide an air intake for said impeller and baffle plates affixed between the said cover sheets and extending obliquely from adjacent the said impeller to the corners of said sheets.

2. An air tempering unit including a pair of spaced parallel circular headers through which a heating or cooling medium is adapted to circulate, a series of transverse conduits connecting said headers around their circumferences, cover sheets attached to the outer sides of said headers, and an air impeller mounted interiorly and centrally of said cover sheets, the front cover sheet being apertured to provide an air intake for said impeller and baffle plates affixed between the said cover sheets and extending outwardly from adjacent the said impeller to the edges of said sheets.

JOHN V. FALCO.
